PEG BENCH OR THE LIKE

Stanley R. Eibetz, Malverne, N. Y.

Application April 8, 1950, Serial No. 9,058

Term of patent 3½ years

(Cl. D33—14)

To all whom it may concern:

Be it known that I, Stanley R. Eibetz, a citizen of the United States, residing at Malverne, in the county of Queens, and State of New York, have invented a new, original, and ornamental Design for a Peg Bench or the like, of which the following is a specification, reference being had to the accompanying drawing, forming part thereof.

In the drawing

Fig. 1 is a perspective view from the right side of a peg bench, showing my new design;

Fig. 2 is a similar view from the left side thereof, and

Fig. 3 is a reduced elevational side view of the peg bench shown in Fig. 1.

I claim:

The ornamental design for a peg bench or the like, substantially as shown.

STANLEY R. EIBETZ.
